UNITED STATES PATENT OFFICE.

JOHN ROGERS, OF NEW YORK, N. Y.

DESIGN FOR A GROUP OF STATUARY.

Specification forming part of Design No. 5,142, dated July 25, 1871.

To all whom it may concern:

Be it known that I, JOHN ROGERS, of the city, county, and State of New York, have invented and produced a new and original Design for a Group of Statuary.

The nature of my design is fully represented in the accompanying photographic illustrations.

The group is called "Rip Van Winkle on the Mountain," and consists of Rip with his dog and the little man with the keg of whisky. Rip is represented as coming down the mountain; his gun is balanced in his right hand, and with his left he is holding back his dog, who has his fore paws resting on Rip's left leg, and is looking fiercely at the little man before them, who is resting a keg on his left knee and pointing at it, while he looks up at Rip to ask him to help him with his load.

I claim as my invention—

The design for a group of statuary, as shown in the above specification.

JOHN ROGERS.
